UNITED STATES PATENT OFFICE.

VERNE E. ELLIS, OF NEW YORK, N. Y.

WINDOW-WASHING DEVICE.

Application filed January 24, 1921. Serial No. 439,705.

To all whom it may concern:

Be it known that I, VERNE E. ELLIS, a citizen of the United States of America, residing at 375 West 126th Street, in the city and county of New York, State of New York, have invented a new and useful Window-Washing Device, of which the following is a specification.

My present invention relates to a device for cleaning and polishing windows, and has for its object the construction of an economical, efficient and safe means for cleaning and polishing windows.

One of the advantages of my device is that the outside of the window may be cleaned therewith from the inside of the room, thereby eliminating the danger in getting out on the window sill or leaning outside of the window to clean the same.

Another advantage of my device is that the corners of the windows are as well cleaned as any other part of the surface.

In the drawings accompanying this specification, and forming a part thereof, Fig. 1 is a back plan view of my device in operative position, showing in dotted lines the compressing springs extended, and in solid lines the same springs compressed, and

Fig. 2 is a side sectional view thereof.

The device herein described and shown by the drawings comprises the rectangular plate 3, of any suitable material, preferably thin brass, having the corners slightly rounded, the plate being provided on its back near each end of the plate with a clamping member 4, having a clamping portion with rectangular extension ends which are hingedly secured to the plate as at 13, the clamping portion when in vertical position being spaced away from the face of the plate by its angular ends and when in this position being adapted to receive between the clamping portion and the face of the plate the upturned ends of the cleaning or polishing pad or cloth later mentioned, the clamping member being movable on its hinged connections downwardly for thereby retaining said pad or cloth in operative position on the plate 3.

The plate 3 is provided with compressing members 5 in the form of spring wire loops, that is, they comprise straight parallel portions connected by a bow portion. The compressing members 5 are fixedly secured at the free ends of their straight portions to the back of the plate 3, as by the

lugs 18, located near the side edges of the plate, the straight portions of said members terminating in hooks 22 extending outwardly from the lugs 18. The lugs 18 which are in opposed relation to each other relative to the ends of the plate 3 are arranged out of alinement, one lug being nearer the edge of the plate than the other, whereby the straight portions of the compressing members 5 are brought into parallelism. The compressing members 5 when in normal position are spaced away by their resiliency from the face of the plate 3 by continually increasing distance, from the point of attachment of the straight portions at 18 to the bow ends of the compressing members, as seen when viewed from the side in Fig. 2.

A cord or flexible band 11, is attached bridle-wise at one end to the hooks 22 of one of the compressing members 5 and a similar cord or band is similarly attached to the hooks 22 of the other compressing member 5, the cords or bands being passed over the bow ends of these members so that the bow ends are between the cords or bands and the plate 3, and the cords or bands bear on the bow ends, whereby strain or pull on the cords or bands causes compression of the compressing members with consequent tendency of the compressing members to press or force the plate 3 against an adjacent parallel surface, in this instance the glass of the window sash.

But, as may be readily understood, it is not essential that the cords or bands 11 should be secured to the compressing members 5, as it is only necessary that they should be secured in any suitable manner to the plate 3 to exert a pull or strain on the plate 3 in the longitudinal line thereof for causing tractive movement of the plate, and that in so doing they should pass over the bow ends of the compressing members 5 for compressing them as described.

Each of the unattached ends of the cords or bands 11 passes over a sheave 2, slidably movable on the rod or shaft 7, which rod is fixedly positionable between the jambs of the window frame, one rod at top and the other rod at the bottom of the frame, by means of the spring maintained extensible pressure members 9 operatively arranged in a well known manner at the ends of the rod 7.

In operation, the pad or cloth 40, Fig. 2, being clamped on the front face of the

plate 3, and the rods 7 being in position at the top and bottom of the window frame, to clean the outside of the glass of the upper sash, the upper sash is lowered and the 5 lower sash is raised to substantially conforming adjacency therewith; the device is then passed over the upper edge of the sashes and by means of one of the cords or bands 11 is permitted to hang face in- 10 ward against the glass of the upper sash; the cord or band supporting the device is passed over the sheave of the upper rod 7 and carried downwardly and the other cord is passed under the lower edge of the lower 15 sash and thence over the sheave of the lower rod and carried upwardly; by tension on the cords or bands the device is pressed against the glass by the compressing members and by alternately pulling on the cords 20 or bands a frictional cleaning or polishing movement of the device is afforded. To clean the outside of the glass of the lower sash, the sashes being closed, the lower sash is raised slightly and one of the cords or bands is passed over the upper edge of the lower sash and permitted to drop between the two sashes, the cords being provided at their unattached ends with small weights, not shown, to facilitate this; the device is 25 then drawn downwardly, through the space between the inner face of the glass of the upper sash and the outer face of the lower sash, the compressing members 5 being compressed or drawn down flat by the tension 30 on the cords or bands during the operation, the space provided between the frame portions of the sashes and the surfaces of the window frames permitting passage of the device, and the device is then operated as 35 before described.

While I have here described the preferred form of my invention, it will be seen that my device is operable without the rods 7 by merely passing the bands 11 over the 40 top and bottom of the window section being cleaned, and it is to be understood that my invention is susceptible of such modifications as come within the scope of the appended claims.

Having thus described my invention, I claim:

1. In a window cleaning device, a plate; flexible means secured to the plate for providing frictional movement of the plate by 50 manual operation of said means; and springs having parallel straight portions connected by bow ends; the straight portions being secured at their terminals to the plate, the bow end of one spring being 55 opposed to the bow end of the other spring and the straight portions of one spring being in parallelism with the straight portions of the other spring, the springs due 60 to their resiliency being spaced away by an increasing distance from the face of the 65

plate for the length of the springs from the points of their attachment to the plate to their bow ends; the flexible means when in operable position bearing on the bow ends of the springs and when manually operated compressing the springs for thereby pressing the plate against the glass of the window. 70

2. In a window cleaning device, a plate; flexible means secured to a face of the plate 75 for providing frictional movement of the plate by manual operation of said means; means adapted for frictional application to the glass of the window for cleaning or polishing the same; means for removably 80 securing said frictional means to a face of the plate; and springs having parallel straight portions connected by bow ends; the straight portions being secured at their terminals to the face of the plate opposite 85 said frictional means, the bow end of one spring being opposed to the bow end of the other spring and the straight portions of one spring being in parallelism with the straight portions of the other spring, the 90 springs due to their resiliency being spaced away by an increasing distance from the face of the plate for the length of the springs from the points of their attachment to the plate to their bow ends; the flexible 95 means when in operable position bearing on the bow ends of the springs and when manually operated compressing the springs for thereby pressing the plate and said frictional cleaning or polishing means against 100 the glass of the window.

3. In a window cleaning device, a thin plate, a relatively thin cleaning or polishing cloth, means on the rear face of the plate 105 engaging the ends of said cloth for retaining the cloth on the front face of the plate, spring members secured to the rear face of the plate and having oppositely extending bow portions normally spaced away 110 from the plate at their ends by the resiliency of the members and compressible to bring the bow portions into positions substantially parallel to the rear face of the plate and adjacent thereto, and flexible means secured 115 to the plate having free ends passing over said bow portions and engageable with the window sash for providing frictional movement of the plate by normal operation of said means and for compressing said bow portions during said frictional movement, the relative thinness of said cloth and said compressibility of the spring members permitting passage of the device through the space afforded between the panes of the upper and lower sashes when the sashes are in partially raised relation for positioning the device on a pane of the lower sash 120 for cleaning or polishing the pane. 125
